3 Claims

ABSTRACT OF THE DISCLOSURE

The file drawer is slidably mounted in a cabinet on a roller suspension. The drawer comprises a main file supporting member and a drawer head. The file supporting member has a bottom wall, a longitudinal side wall and two opposite laterally extending end members. The top and the longitudinal side opposite the side wall of the drawer are open for insertion and removal of files. The drawer head may be mounted on either end member so that the file supporting member may be positioned in the cabinet with the single longitudinal side wall on one side or the other.

RELATED APPLICATION

This is related to my copending application Ser. No. 641,363 filed May 25, 1967 and entitled "Filing Cabinet" now U.S. Pat. No. 3,433,548 dated Mar. 18, 1969.

BACKGROUND OF THE INVENTION

Drawers for filing papers and documents are inserted only in one way into the cabinet and the front panel or drawer head is mountable only at one end. In the aforementioned related application an endwise inserted file drawer is described in which one side is open for passing files. The opening is either on the left or right side and cannot be changed.

SUMMARY OF THE INVENTION

The file drawer has a bottom wall, one side wall and two end members at opposite ends. The drawer can be fitted in the file cabinet to place the side wall on one side or the other, and the drawer head can be mounted on either of the end members. Thus the drawer is reversible to reverse the position of the open side.

An object of the invention is to provide a file drawer in which the closed side and the open side can be reversed in position.

Another object of the invention is to provide a file drawer with a main file supporting member having means for mounting the drawer head at either end of the drawer and inserting the end without the header into the filing cabinet.

Other and further objects will be apparent from the following description taken in connection with the drawings.

BRIEF DESCRIPTION OF THE DRAWINGS

FIG. 1 is a perspective view of the filing cabinet with the drawer extended and open on the left side.

FIG. 2 is a perspective view of the filing cabinet with the drawer extended and open on the right side.

FIG. 3 is a perspective view of the file supporting member with the header spaced from one end.

FIG. 4 is a vertical longitudinal sectional view of the drawer taken along lines 4—4 of FIG. 3.

FIG. 5 is a fragmentary horizontal longitudinal sectional view of the drawer taken along lines 5—5 of FIG. 4.

FIG. 6 is an enlarged vertical sectional view of the header taken along lines 6—6 of FIG. 2.

FIG. 7 is a lateral sectional view of the drawer recessed in the cabinet.

DETAILED DESCRIPTION

Referring to the drawings a file drawer 10 is supported by a roller suspension 11 (FIG. 7) for moving the drawer 10 in and out of the cabinet 12, as fragmentarily shown.

5 The filing cabinet 12 is of the conventional type and has rails 13 (FIG. 7) mounted on lateral beams 14. The roller suspension 11 supports the drawer on the rails 13 in rolling relation therewith. The roller suspension 11 has two support members 15, 16 with rollers 17, 18 and 19, 20, respectively. Two generally S-shaped longitudinal members 21, 22 extend downward from the bottom wall 26 of the drawer. The rollers engage the rails and S-shaped members to support the drawer.

10 The drawer 10 comprises a file supporting member 25 (FIG. 3) having a horizontal bottom wall 26 and an upwardly extending side wall 27 along one edge and a downwardly extending side wall 28 along the other edge. The top of the drawer 10 is open and the longitudinal side opposite to the side wall 27 has an opening 29. Files may be inserted from the top or from the side in a generally horizontal direction. The side wall 30 (FIGS. 2 and 7) extends downwardly from the vertical side wall 27 to form a space 31 enclosed on the top and sides for receiving the roller suspension 11.

15 At the ends of the file supporting member 25 are end members 32, 33 (FIGS. 3, 4 and 5) mounted on the side wall 27 and the bottom wall 26. The end members project upwardly normal to the bottom and side walls to close the ends of the supporting member 25. The end members 32, 33 comprise panel members 34, 35 with four flanges 36, 37, 38, 39 and 40, 41, 42, 43, respectively, perpendicular thereto. The flanges have openings 44 for passing machine screws 45 (FIGS. 3 and 6). On the open side of the file supporting member are straight braces 46, 47 fastened to the side wall 28 and the flanges 36 and 40.

20 The drawer head or header 50 has a front panel 51 and four edge walls 52, 53, 54 and 55. The edge walls 52, 53, and 54 have flanges 56, 57 and 58, respectively, interfitting with the flanges 36, 37 and 38 of the end member 32. Machine screws 45 fasten the flanges together.

25 Notches 60 and 61 are provided in the flanges 56 and 58 for accommodating the flanges 39 and 43 and the bottom wall 26. The flanges 56, 57, 58 are formed by bending the edge walls 52, 53 and 54 in a generally Z shape, as illustrated in FIG. 6. The bottom edge wall 55 is bent in a generally L shape to support a reinforcing member 62 having a flat U shape with an upper flange 63. The handle 64 of the drawer is fastened to the front panel 51 with the bolts 65 passing through the front panel and the flange and bearing thereagainst. The reinforcing member may also be used to support a locking mechanism, not shown. Also, resilient bumpers 66 are provided to engage the roller suspension 11 on closing of the drawer. The bottom wall 26 and side wall 27 have notches 67 and 68, respectively, for receiving tabs 69, 70 on separators 71 mounted on the supporting member, as best illustrated in FIGS. 1 and 2.

30 The file drawer may be completely removed from the cabinet and dismounted from the roller suspension 11 by tilting the catches 72 so as to pass the pivotally mounted stops 73 or 74 depending upon the direction the drawer is fitted into the file cabinet. The machine screws 45 are removed so that the drawer head or header 50 can be dismounted from one end member and mounted on the other end member. The S-shaped longitudinal members 21 and 22 extend the full length of the file supporting member so that they may be fitted into the roller suspension from either end of the file supporting member. The file supporting member is symmetrical about a vertical center plate extending laterally across the file supporting member.

Thus it is seen that the file drawer described in my copending application Ser. No. 641,363 has been modified so that the file supporting member of the drawer can be reversed to position the side wall on either side of the drawer. Thus the file inserting opening may be placed on either side of the drawer depending upon the requirements of the location of the file. The reversal of the file supporting member is easily accomplished by removing the drawer from the roller suspension and dismounting the header in a simple manner, and remounting it on the other end of the file supporting member.

As in my previous file cabinet, the cabinet 12 may be stacked, and has all of the advantages of that file cabinet in addition to the reversible feature.

In the drawings FIGS. 4, 5, 6 and 7 are in proportion to the file drawer as designed and built.

Various modifications may be made in the foregoing embodiment without departing from the invention as set forth in the appended claims.

I claim:

1. A file drawer for being removably contained within a cabinet comprising a bottom wall, a side wall extending along one side of said bottom wall, end members attached to opposite ends of said bottom and side walls forming a file space, the opposite side of said drawer from the said side wall being open for transferring files to and from said file space, mounting means on opposite sides of said drawer bottom wall for movably maintaining it on said cabinet, said mounting means on one side being symmetrical with the means on the opposite side whereby said drawer may be mounted on said cabinet with either end member innermost, a header having means for detachably mounting it on either of said end members whereby said file drawer may be positioned in the cabinet with the header outermost and said side wall on one side or the

other, said end members including flanges adjacent to the periphery of said end members and lateral thereto and said header having flanges for interfitting with said flanges on either end member.

5 2. A file drawer as set forth in claim 1 wherein said end members are positioned above said bottom wall with lower flanges of said end members being on top of said bottom wall and with flanges on the sides of said header having notches to receive said bottom wall and lower flanges of said end means.

10 3. A file drawer as set forth in claim 1 characterized by said drawer mounting means comprising S-shaped members extending longitudinally of said bottom wall from one end member to the other for fitting in a roller suspension from either end.
